BUFFING WHEEL

Application filed February 18, 1930. Serial No. 429,265.

This invention relates to improvements in buffing wheels which are formed of a plurality of thin disks of fibrous material which are secured together and mounted upon a rotating mandrel, the work to be polished or buffed being held against the periphery of the assembled disks. It has previously been the custom to secure such disks together in assembled position by a spiral row of stitching 5 extending from the central portion of the disk to the periphery thereof, the spirals being spaced at different distances according to the desired stiffness of the buffing wheel. In other instances, the disks have been secured together by lines of stitching extending at right angles to each other and crossing each other to form pockets to receive polishing material which frequently is applied to the periphery of the buffing wheel. 10 In usual constructions the wearing away of the periphery of the wheel breaks out the stitches at the periphery and permits the disks to flex at irregular portions of the periphery, thereby preventing the wheel 15 from producing a uniform polishing action upon the material.

The object of the present invention is broadly to provide a buffing wheel comprising a plurality of assembled thin disks of fibrous material secured together by lines of stitches presenting repeated zigzagged designs in which the stitches extend alternately in different directions and preferably in which each stitch extends in an abruptly different direction from the next preceding stitch of said design and which stitches join the plies together at closely adjacent intervals, so that the wearing away or breakage 30 of any stitch will not free the plies of fabric for any substantial distance inwardly from the worn periphery.

The invention contemplates broadly the assemblage of a plurality of thin fibrous disks by lines of stitches of this character in any desired manner according to the softness or hardness of the desired working peripheral surface of the disk, whereby the disk will be worn with substantial uniformity throughout its periphery. Desirably the 40 buffing wheel comprises a central area in

which the plies of fibrous material are secured together by spiral lines of plain stitching with the spirals thereof arranged at such intervals as will provide the desired degree of rigidity. Where a soft disk is required the plies of the outer zone of the wheel may be secured together by radial lines of stitching of the character above described arranged at suitable intervals. Where a relatively 55 hard buffing wheel is required the peripheral zone, which forms the working area of the wheel, desirably is provided with a wide line or wide lines of stitching presenting zig-zagged patterns which are substantially concentric with the periphery of the disks and in which the stitches join the disks at such close intervals that the wearing away of the stitches at the periphery will not materially loosen the other stitches which join the disks together, thereby maintaining the peripheral 60 buffing surfaces substantially uniform until the disks are worn down substantially to the depth of said working zone.

A further object of the invention is to provide a buffing wheel comprising a plurality of assembled thin disks of fibrous material having a peripheral zone forming the working area in which the disks are secured together by a spiral line of stitches presenting a repeated design in which each stitch of the 75 design extends in a different direction from the next preceding stitch of the design and in which the stitches are relatively short and join the plies together at closely adjacent intervals both radially and peripherally.

A further object of the invention is to join the disks by a concentric or spiral line of stitches presenting a repeated zigzag design of such character that the area of the design of successive concentric circles or successive spirals will overlap the area of the design of the next outer concentric line or spiral, and in which the stitches of the design of one line will seldom, if ever, intersect the stitches 80 of an adjacent line or spiral.

These and other objects and features of the invention will more fully appear from the following description and the accompanying drawing and will be particularly 95 pointed out in the claims.

In the drawing:

Fig. 1 is a plan view of a buffing wheel comprising a plurality of assembled disks in which the disks are secured together throughout the peripheral zone forming the working area by a spiral line of stitches presenting repeated designs in which the stitches extend alternately in abruptly different directions and join the plies at closely adjacent intervals;

Fig. 2 is a plan view of a buffing wheel comprising a plurality of assembled disks having a central zone secured together by a spiral line or lines of plain stitches with a peripheral or working zone in which the plies of fibrous material are secured together by radial lines of stitches presenting repeated zigzag designs in which the stitches extend alternately in different directions and join the plies together at closely adjacent intervals;

Fig. 3 is a plan view of a buffing wheel in which the lines of stitching presenting the repeated zigzag design are concentrically arranged in the working zone and having also radial lines of stitching of like character;

Fig. 4 is an enlarged sectional view of the edge of the disk illustrating the manner in which the stitches are concatenated and serve to join the disks together at closely adjacent intervals; and,

Fig. 5 is an edge view of a buffer comprising a plurality of buffing wheels of the character described clamped upon a rotating arbor.

The buffing wheel, as illustrated in Fig. 1 of the drawing, comprises a plurality of fibrous disks 1 which may be of cotton fabric, such as cotton duck, or other suitable material, which desirably are assembled in such angular relation to each other as to stagger the direction of the lines of warp and weft in the respective disks or plies. The disks 1 are assembled with the flat faces thereof of contacting with each other and are provided with a central zone 2 in which the assembled disks are secured together by a spiral line of usual straight stitches 3. In the peripheral or working zone 4 the disks or plies of fibrous material are secured together by a wide spiral line of stitching 5 presenting a repeated zigzag design in which the stitches extend alternately in different directions and in which each stitch preferably extends in an abruptly different direction from the next preceding stitch in the design.

In this construction each stitch extends in a direction at right angles to the next preceding in such a manner as to form connected zigzagged trefoil designs 6 and 7 which lie on opposite sides of a median line representing the direction of the line of stitching or in a zig-zag course. By reason of this construction certain of the stitches extend in substantially radial directions while others

extend in directions substantially concentric with the periphery of the wheel and the anchorages afforded by these stitches are closely adjacent to each other both radially and circumferentially.

The areas of the respective designs of the successive spirals desirably slightly overlap without intersection of the threads forming the designs of successive spirals. By reason of this construction the disks or plies of fibrous material are anchored together at very closely adjacent intervals both radially and circumferentially. The stitches uniting the layers of fibrous material desirably are lock stitches with the needle thread maintained under sufficient tension to draw the concatenating loops of the needle thread and locking thread well into the interior of the buffing wheel, so that where the concatenated thread is worn out during the buffing operation the release of the ends of such worn thread will not cause unravelling of the next preceding stitch which likewise is locked into the body of the assembled buffing wheel.

It, therefore, follows that as the wheel wears a substantially uniform surface is maintained and this is particularly important where a series of buffing wheels are assembled together, as illustrated in Fig. 5, to produce a buffer for relatively large surfaces.

The concatenations of the stitches are illustrated in Fig. 4 which shows a group of needle thread exposed and concatenated with the loop of locking thread, with the next concatenating loop of each embedded sufficiently into the material to hold the plies together until the wheel has worn down to such loop.

In Fig. 2 a soft buffing wheel is illustrated in which the disks or plies of fibrous material are secured together by substantially radial lines of stitching of the same character and comprising lines of stitches presenting a repeated design in which the stitches extend alternately in different directions and join the plies of the buffing wheel throughout the area of the radial line of stitching at closely adjacent intervals.

The repeated designs of the lines of stitching desirably are arranged in zig-zag relation to secure the plies of fabric together through radial areas of substantial width, thereby very materially stiffening the disk, so that when in use it will not readily buckle when the article being buffed is pressed against it. Such stiffening of the disk not only increases the efficiency, but also materially increases the length of life of the disk.

The portion of the buffing wheel between the radial lines of stitching may be relatively free, as illustrated, or the buffing wheel may be provided with a suitable relatively hard zone, as illustrated in Fig. 1, in which case the radial lines of stitches will secure the

disks or plies of fibrous material together along radial lines separated from each other at suitable intervals, while the disks at the peripheral zone or working area of the wheel 5 will be secured together by concentric or spiral lines of stitches of the character above described. Such a construction is illustrated in Fig. 3 in which a plurality of concentric circular lines of stitches of the character 10 above described serve to secure the disks or plies of fibrous material together at the peripheral or working zone, while the disks are secured together at an intermediate or central zone by radial or spiral lines of 15 stitching.

It will be understood that the particular embodiment of the invention which is disclosed herein is of an illustrative character and is not restrictive, and that various 20 changes in form and design may be made within the spirit of the invention and of the following claims, provided that the stitches, which form the design of the line of stitching, are so arranged as to join the disks or plies 25 of the buffing wheel at such close intervals and in such manner that the wearing away of one or more stitches of the design will not cause or permit substantial separation of the plies any considerable distance from the 30 peripheral working edge of the buffing wheel.

Having thus described the invention, what is claimed as new, and desired to be secured by Letters Patent, is:

1. A buffing wheel comprising a plurality 35 of assembled thin circular disks of fibrous material having a peripheral zone forming the working area sewed together by a wide spiral line of stitching formed of a succession of short stitches presenting repeated 40 zigzagged designs in which each stitch ex-

tends in an abruptly different direction from the next preceding stitch and in which the areas of the designs of each inner convolution of the spiral overlaps a portion of a like design in the adjacent outer convolution without intersection of the stitches thereof, and whereby the stitches join the plies at closely adjacent intervals. 70

2. A buffing wheel comprising a plurality of assembled disks of thin fibrous material having a peripheral zone forming the working area sewed together throughout said working area by a wide narrowly spaced spiral line of stitching formed of a succession of short stitches presenting a repeated zigzagged 75 trefoil design and in which the area of the design of each inner convolution overlaps an area of a like design of the next outer convolution without intersection of the stitches forming the respective designs. 80

3. A buffing wheel comprising a plurality of assembled disks of thin fibrous material having a peripheral zone forming the working area sewed together throughout said working area by a wide narrowly spaced spiral line of stitching formed of a succession of short stitches presenting a repeated zigzagged trefoil design and in which the area of the design of each inner convolution overlaps an area of a like design of the next 90 outer convolution without intersection of the stitches forming the respective designs, and a plurality of radial wide lines of short stitches presenting repeated zigzagged trefoil designs extending from approximately the 95 center of the wheel to the working area thereof.

In testimony whereof, I have signed my name to this specification.
